UNITED STATES PATENT OFFICE.

CHARLES MILLER, OF LONG ISLAND CITY, NEW YORK.

WINDOW-OPERATING APPARATUS.

Application filed March 20, 1925. Serial No. 16,972.

This invention relates more particularly to a class of apparatus for use in conjunction with windows.

My invention has for its object primarily to provide a mechanism designed to be employed in buildings and other structures for raising and lowering a single sash of a window or raising and lowering the lower and upper sashes of the window in unison as well as capable of being made for raising and lowering the sashes different consecutive distances, and which is electrically operative for enabling the apparatus to be operated by one or a number of switches to avoid manual exertion when desired to open and shut the window, besides enabling the switches to be so arranged whereby a person while lying in bed may cause the apparatus to be operated for raising and lowering the sashes for overcoming the requirement to leave the bed.

The invention consists essentially of attaching cables to a single sash or to the lower and upper sashes of a window, and mechanism is provided for moving the cables to raise and lower the single sash or to raise and lower both sashes simultaneously. The mechanism is operated by an electric circuit, and the circuit may be closed and opened by one or a number of independently operative switches. Interposed in the circuit is means which is adjustable for controlling the circuit to operate the mechanism for raising the single sash or for raising the lower sash and lowering the upper sash in unison and to cause the mechanism to reversely operate for subsequently lowering the single sash or for subsequently lowering the lower sash and raising the upper sash in unison. When a number of the separately operative switches are employed a controller is provided in the circuit for being operated with the closing of the circuit by operation of each switch to operate the mechanism for raising and lowering the sashes determined consecutive distances, in order that the windows may be suitably opened and closed without manual effort or allowing the sashes to be raised and lowered different heights while a person occupies a bed or the like.

A further object of the invention is to provide a window operating mechanism of a simple, efficient and durable construction which may be made of appropriate forms adapted for use with windows of various sizes and types.

With these and other objects in view, the invention will be hereinafter more fully explained with reference to the accompanying drawings forming a part of this specification in which similar characters of reference indicate corresponding parts in all the views and will then be pointed out in the claims at the end of the description.

In the drawings, Figure 1 is a fragmentary view showing an elevation of a window taken on the line 1—1 of Fig. 2, and which shows parts of my improved mechanism applied thereto.

Fig. 2 is a sectional view, partly in detail, taken on the line 2—2 of Fig. 1.

Fig. 3 is a detail sectional view, partly fragmentary, taken on the line 3—3 of Fig. 1.

Fig. 4 is an enlarged sectional view, partly fragmentary and partly in detail, taken on the line 4—4 of Fig. 2, and

Fig. 5 is a diagrammatic view of the electric circuit for operating the apparatus with an elevation of the controller used in the apparatus.

The apparatus 10 may be applied to any suitable form of window, as A, of a building or other structure, having a single sash or having a lower sash, as B and an upper sash, as C, which may be counterbalanced in the usual manner by two or more weights, as D, E. Included in the apparatus 10 are two cables, 11, 12 operatively arranged with in the frame, as F, of the window at the sides of the sashes B, C. Part of the cable 11 is attached by means of a bracket 13 to the lower portion of one of the side edges of the lower sash B of the window, and part of this cable is attached by means of another bracket 14 to the lower part of one of the side edges of the upper sash C of the window. Part of the cable 12 is secured by means of a bracket 15 to the lower portion of the other side edge of the lower sash B, and part of the cable 12 is secured by means of a bracket 16 to the lower portion of the second side edge of the upper sash C of the window.

The front part of the sill G of the frame F of the window under the sashes may be recessed lengthwise, as at H, and in spaced parts of the rear portion of the sill at the lower end of the cables 11, 12 may be recessed, as at I and J, and these spaced recesses communicate with the recess H. On the wall of the recess I of the sill of the

window is a bracket or bearing 17 in which is journaled one end of a short shaft or stud 18 which extends into the recess H, and on this stud is a drum 19 on which the cable 11 is wrapped. In bearings 20 provided in the upper part of the frame F of the window is journaled the ends of a short shaft or stud 21, and on this stud is a drum 22 on which the cable 11 is also wrapped. On the wall of the recess J of the sill G of the window is a bracket or bearing 23 in which is journaled one end of a short shaft or stud 24 which extends into the recess H, and on this stud is a drum 25 on which the cable 12 is wrapped. In bearings 26 provided in the upper part of the frame F of the window is journaled the ends of a short shaft or stud 27, and on this stud is a drum 28 on which the cable 12 is also wrapped. The drums 19 and 22 are so spaced apart that the cable 11 is held movably taut thereon, and the drums 25 and 28 are likewise spaced apart so that the cable 12 is held movably taut thereon. The cables 11 and 12 are also of sufficient lengths when operated to permit the lower sash of the window to be raised and lowered different consecutive distances and simultaneously therewith to permit the upper sash to be raised and lowered different consecutive distances.

The drums and cables form parts of a mechanism 29 which is operative for raising and lowering the sashes. The mechanism 29 may be of any appropriate type, though the form of the mechanism shown has a shaft 30 disposed in the recess H of the sill G of the window below the studs 18, 21 of the drums 19 and 25, and this shaft is journaled in spaced bearings 31, 32 provided on the bottom of the recess H of the sill of the window. On the part of the shaft 30 under the stud 18 of the drum 19 is a worm 33, and meshing with this worm is a worm gear 34 held on the stud 18 of the drum 19. On the part of the shaft 30 under the stud 24 is another worm 35, and meshing with this worm is a worm gear 36 held on the stud 24.

The shaft 30, worm gears 33, 34 and 35, 36 are operated preferably by an electric circuit, as 37 Fig. 5. The circuit 37 may derive its current from any suitable source of electrical energy, such as a battery 38, and the circuit leads to a motor 39 of any well known or preferred reversible type which is provided for driving the shaft 30 of the mechanism 29. The circuit 37 is adapted to be closed and opened by one or a number of switches 40, 41, 42 preferably of push plug types which may be provided in the room of a building having the window so that an occupant of a bed or the like may conveniently operate the switches without leaving the bed. Also interposed in the circuit 29 is another switch 43 of a suitable form 65 which is preferably arranged in proximity to

the switches 40, 41, 42 for being operated to control the circuit for operating the motor 39 from left to right and reversely with the closing of the circuit by the selective operation of the switches 40, 41, 42, as will be hereinafter more fully explained.

Serving to allow the sashes of the window to be synchronously raised and lowered determined consecutive distances, in the recess H of the sill G of the frame of the window and adjacent the stud 24 of the drum 25 is a controller, as 44, Figs. 2, 4, 5. The controller 44 is preferably of a form having a base plate 45 which protrudes from the end wall of the recess H of the sill of the window so that the central part of the base plate is in front of the stud 24 of the drum 25. On the face of the base plate 45 opposed to the forward end of the stud 24 is an annular insulating plate 46, and embedded in the exposed face of the insulating plate are three conductive contact plates, as 47, 48, 49. These contact plates are of arc-shapes of curvatures so that they are relatively disposed in the fashion of a circle in surrounding positions relative to the stud 24, and the contact plates are of such lengths that their ends are spaced from each other. The parts of the insulating plate 46 between the ends of the contact plates provide interrupters, as 50, 51, 52, for shutting off the current of the circuit at determined intervals, and in the interrupting spaces 50, 51, 52 of the insulating plate 46 midway between the opposed ends of the contact plates 47, 48, 49 are contacts or conductive small plates or blocks 53, 54, 55. The insulating plate 46 is larger in diameter than the diameter of the annular contact plates 47, 48, 49 to provide an outer marginal edge 56 surrounding the contact plates, and in this marginal edge are spaced notches or stops 57, 58, 59 each in proximity to the contact blocks 53, 54, 55. Fixed on the end of the stud 24 opposed to the insulating plate 46 is an insulating sleeve 61, and on the outer periphery of this insulating sleeve is a conductive collar 62 having a conductive arm or bracket 63. The conductive bracket 63 is of an angular shape disposed in closely spaced relation crosswise of the contact plates 47, 48, 49, and this conductive bracket with its head, as 64, are adapted to movably engage the notches 57, 58, 59 of the insulating plate 46. In part of the conductive bracket opposed to the contact plates 47, 48, 49 is a recessed member, as 65, and yieldingly movable inwardly and outwardly of the mouth of this recessed member is a contact pin 66 having a stem 67 movably disposed through a hole in the bottom wall of the recessed member. The head 68 of the contact pin 66 movably engages the exposed face of the contact plates 47, 48, 49, and in the recessed member 65 surrounding the stem 67 of the contact

pin 66 is a spiral spring 69 tensioned for thrusting the pin so that its head 68 is forced to yieldingly engage the contact plates 47, 48, 49 when the bracket 63 is rotatively swung by the driving of the stud 24 and the insulating sleeve 61. The conductive collar 62 of the conductive bracket 63 is movably engaged by a conductive spring contact strip, as 70, which is suitably supported and interposed in the circuit as well as interposing the collar 62, bracket 63 and contact pin 66 in the circuit 37.

The switch 43 of the electric circuit 37 may be of a form having two spaced connected arms 71, 72 which are pivoted, at 73, and one end of the arm 72 of the switch is connected to a wire 74 leading from one terminal of the battery 38. From the second terminal of the battery is a wire 75 leading to each of the switches 40, 41, 42, and from this wire 75 is a wire 76 which leads to the contact plate 49 of the controller 44. Connected to one end of the arm 71 of the switch 43 is a wire 77 which leads to the conductive spring strip 70. The second ends of the arms 71, 72 of the switch 43 are adapted with the pivotal adjustment of the switch 43 to detachably engage two of three contacts 78, 79, 80. Leading from the contact 80 to one of the terminals of the motor 39 is a wire 81, and connected to the wire 81 is a wire 82 which leads to the contact 78. Connected to the contact 79 is a wire 83 which leads to the second terminal of the motor 39. To the wire 76 is connected a wire 84 which leads to the contact plate 48 of the controller 44, and also connected to the wire 76 is another wire 85 leading to the contact plate 47 of the controller. The contact block 53 of the controller 44 is interposed in the circuit by a wire 86 which leads to the push plug switch 40. Leading from the switch 41 to the contact block 54 is a wire 87, and leading from the switch 42 to the contact block 55 is a wire 88. The head 68 of the conductive contact pin 66 is larger than the width of each of the contact blocks 53, 54, 55.

When it is desired to simultaneously raise the lower sash B and lower the upper sash C of the window determined distances, the switch 43 is moved for example so that its arms 71 and 72 engage the contacts 78, 79, as shown in Fig. 5. When the push switch 40 is then operated the circuit will be closed from the battery over wire 75 to the switch 40, and from the battery the circuit will be closed over wire 74, through the arm 72 of the switch 43, and over wire 83 to one terminal of the motor 39. The circuit will be closed from the switch 40, over wire 86, through the contact block 53, through the contact pin 66, through the bracket 63, through the collar 62, through the spring strip 70, over wire 77, through the arm 71 of the switch 43, over wire 82 and over wire

81 to the second terminal of the motor 39. The circuit will also be closed from the battery over wire 75, over wire 85 to the contact plate 47. The motor will then operate to drive the shaft 30 and worm gears 33, 34 and 35, 36 which in turn will rotate the studs 18, 24 for revolving the drums 19, 25, and the cables 11, 12 will move to simultaneously raise the lower sash and lower the upper sash the desired distances. With the rotation of the stud 24 the bracket 63 of the controller 44 will move from left to right for causing the head 68 of the contact pin 66 to move on the contact plate 47 its entire length. The impetus of the motor will carry the bracket 63 sufficient distance beyond the contact plate 47 for causing the head 68 of the pin 66 to jump the interrupting space 51 so that the head of the pin will move upon the contact block 54. The contact blocks 53, 54, 55 are proportioned and spaced from the ends of the contact plates 47, 48, 49 to allow the bracket 63 and pin 66 to move from each contact plate to the next adjacent contact block, and to move from each contact block to the next adjacent contact plate in each successive step in the operation of the apparatus. Moreover, the contact plates 47, 48, 49 are of such lengths to enable the circuit to be closed for such a period that each step in the operation of the apparatus will cause the sashes of the windows to be raised and lowered determined distances, the circuit being opened when the pin 66 of the bracket 63 moves from the contact plate 47 and jumps the interrupting space 51, as explained.

When it is desired to simultaneously raise the lower sash B and lower the upper sash C of the window additional determined distances, the push switch 41 is operated, the switch 43 remaining in its present position with its arms engaging the contacts 78, 79 of the wires 81, 83. The circuit will be closed from the battery 38, over wire 75 to the switch 41, and from the battery the circuit will be closed over wire 74, through the arm 72 of the switch 43 and over wire 83 to one terminal of the motor 39. From the switch 41 the circuit will be closed over wire 87, through the contact block 54, through the contact pin 66, through the bracket 63, through the collar 62, through the spring strip 70, over wire 77, through the arm 71 of the switch 43, over wire 82 and over wire 81 to the second terminal of the motor 39. The circuit will also be closed from the battery 38, over wire 75, over wire 76 and over wire 84 to contact plate 48. The motor will then operate to drive the shaft 30 and worm gears 33, 34 and 35, 36 which will rotate the studs 18, 24 for revolving the drums 19, 25, and the cables 11, 12 will simultaneously move for raising the lower sash and lowering the upper sash the desired distances. With the

rotation of the stud 24 the bracket 63 of the controller 44 will move for causing the head 68 of the contact pin 66 to move on the contact plate 48 its entire length, and the impetus of the motor will carry the bracket 63 beyond the contact plate 48 for causing the head 68 of the pin 66 to jump the interrupting space 52 so that the head of the pin will engage the contact block 55 with the head 64 of the bracket being seated in the notch 59 of the insulating plate 46.

When it is desired to simultaneously raise the lower sash B and lower the upper sash C of the window still further determined distances, the push switch 42 is operated, while the switch 43 remains in its present position. The circuit will be closed from the battery 38, over wire 75 to the switch 42, and from the battery the circuit will be closed over wire 74, through the arm 72 of the switch 43 and over wire 83 to one terminal of the motor 39. From the switch 42 the circuit will be closed over wire 88, through the contact block 55, through the contact pin 66, through the bracket 63, through the collar 62, through the spring strip 70, over wire 77, through the arm 71 of the switch 43, over wire 82 and over wire 81 to the second terminal of the motor. The circuit will also be closed from the battery, over wire 75 and over wire 76 to contact plate 49. The motor will then operate to drive the shaft 30 and worm gears 33, 34 and 35, 36 which will drive the studs 18, 24 for revolving the drums 19, 25, and the cables 11, 12 will simultaneously move for raising the lower sash and lowering the upper sash the desired distances. With the driving of the stud 24 the bracket 63 of the controller 44 will move for causing the head 68 of the contact pin 66 to move on the contact plate 49 its entire length, and the impetus of the motor will carry the bracket 63 beyond the contact plate 49 for causing the head 68 of the pin 66 to jump the interrupting space 50 so that the head of the pin 66 will engage the contact block 53 with the head 64 of the bracket 63 being seated in the notch 59 of the insulating plate 46. The window of a room of a building may thereby be suitably opened by the raising of the lower sash and lowering of the upper sash three successive determined distances. When it is desired to close the window by lowering the lower sash and raising the upper sash consecutive distances the switch 43 is swung so that its arms 71, 72 engage the contacts 79, 80 of the wires 81, 83 which lead to the motor 39. By then operating the switch 42, then the switch 41 and then the switch 40 at successive intervals the circuit will be successively closed for reversely operating the motor which in turn will reversely operate the parts of the mechanism 29 and the controller 44 to cause the sashes to be moved to close the window with-

out requiring a person occupying a bed or the like in a room to leave the same to close the window.

In the foregoing description, I have embodied the preferred form of my invention, but I do not wish to be understood as limiting myself thereto, as I am aware that modifications may be made therein without departing from the principle or sacrificing any of the advantages of this invention, therefore, I reserve to myself the right to make such changes as fairly fall within the scope thereof.

Having thus described my invention, I claim as new and desire to secure by Letters Patent:—

1. The combination with a window, of two cables movably supported at each side of the window and both cables attached to the lower and upper sashes, a shaft rotatably mounted crosswise of the window, a reversible electric motor for driving the shaft, means operative by the shaft to move the cables for simultaneously raising the lower sash of the window and lowering the upper sash of the window, an electric circuit leading to the motor, means for controlling the circuit to drive the motor in one direction and to reversely operate the motor, three independently operative switches for closing and opening the circuit at successive intervals, and a controller in the circuit operative with the operation of each of the switches to operate the motor, shaft, and said shaft operative means for moving the cables to raise and lower in unison the sashes of the window determined consecutive distances.

2. The combination with a window, of a pair of rotative drums, one at each side of the upper part of the window, a second pair of rotative drums, one at each side of the lower part of the window, two cables each movable over the drums at each side of the window and both cables attached to the lower and upper sashes, a shaft rotatably mounted crosswise of the window, a reversible electric motor for driving the shaft, gearing operative by the shaft for operating the lower pair of drums to operate the cables for simultaneously raising the lower sash of the window and lowering the upper sash of the window, an electric circuit leading to the motor, means for controlling the circuit to drive the motor in one direction and to reversely operate the motor, three independently operative switches for closing and opening the circuit at successive intervals, and a controller in the circuit operative with the operation of each of the switches to operate the motor, shaft, gearing and lower pair of drums for moving the cables to raise and lower in unison the sashes of the window determined consecutive distances.

3. The combination with cables and mech-

anism operative for moving the cables for raising the lower sash and lowering the upper sash in unison and reversely operative to move the cables for lowering the lower sash and for raising the upper sash also in unison, of independently operative switches each for opening and closing the circuit at successive intervals, means adjustable for controlling the circuit to operate said mechanism and cables for simultaneously raising the lower sash and lowering the upper sash by operating each of the switches to close the circuit and to cause the mechanism and cables to reversely operate for simultaneously lowering the lower sash and raising the upper sash by subsequently operating each of the switches to close the circuit, and a controller in the circuit operative with the operation of each of the switches to operate the mechanism and cables for raising and lowering the sash determined consecutive distances.

4. The combination with two cables attached to the lower and upper sashes of a window, of a shaft rotatably mounted crosswise of the window, a reversible electric motor for driving the shaft, means operative by the shaft to move the cables for simultaneously raising the lower sash of the window and lowering the upper sash of the window, an electric circuit leading to the motor, means for controlling the circuit to drive the motor in one direction and to reversely operate the motor, independently operative switches for closing and opening the circuit at successive intervals, and a controller in the circuit operative with the operation of each of the switches to operate the motor, drum operative means and lower pair of drums for moving the cables to raise and lower in unison the sashes of the window determined consecutive distances.

5. The combination with a pair of rotative drums, one at each side of the upper part of a window and a second pair of rotative drums, one at each side of the lower part of the window, of two cables each movable over the drums at each side of the window and both cables attached to the lower and upper sashes, a shaft rotatably mounted crosswise of the window, a reversible electric motor for driving the shaft, means operative by the shaft for operating the lower pair of drums to operate the cables for simultaneously raising the lower sash of the window and lowering the upper sash of the window, an electric circuit leading to the motor, means for controlling the circuit to drive the motor in one direction and to

reversely operate the motor, and a switch for closing and opening the circuit to operate the motor, shaft, and lower pair of drums for moving the cables to raise and lower in unison the sashes of the window.

6. The combination with a pair of rotative drums, one at each side of the upper part of a window and a second pair of rotative drums, one at each side of the lower part of the window, of two cables each movable over the drums at each side of the window and both cables attached to the lower and upper sashes of the window, a reversible electric motor, means operative by the motor for operating the lower pair of drums to operate the cables for simultaneously raising the lower sash of the window and lowering the upper sash of the window, an electric circuit leading to the motor, means for controlling the circuit to drive the motor in one direction and to reversely operate the motor, independently operative switches for closing and opening the circuit at successive intervals, and a controller in the circuit operative with the operation of each of the switches to operate the motor, drum operative means and lower pair of drums for moving the cables to raise and lower in unison the sashes of the window determined consecutive distances.

7. The combination with a pair of rotative drums, one at each side of the upper part of a window and a second pair of rotative drums, one at each side of the lower part of the window, of two cables each movable over the drums at each side of the window and both cables attached to the lower and upper sashes of the window, means for operating the lower pair of drums to operate the cables for simultaneously raising the lower sash of the window and lowering the upper sash of the window, an electric circuit for operating said means, independently operative switches for closing and opening the circuit at successive intervals, and a controller in the circuit operative with the operation of each of the switches for closing the circuit to operate the drum operative means for moving the cables to raise and lower in unison the sashes of the window determined consecutive distances.

This specification signed this 19th day of March A. D. 1925.

CHARLES MILLER.
